UNITED STATES PATENT OFFICE

WILLIAM B. McNAUGHTON, OF FAIRFIELD, CONNECTICUT, ASSIGNOR TO THE GRANT MANUFACTURING AND MACHINE COMPANY, OF BRIDGEPORT, CONNECTICUT, A CORPORATION OF CONNECTICUT

ROTATABLE HEAD FOR RIVET-SPINNING MACHINES

Application filed May 9, 1929. Serial No. 361,612.

This invention relates to new and useful improvements in rivet spinning machines, and more particularly to the spinning head or tool, for forming heads upon rivet ends as in the act of riveting two pieces of metal together.

The invention is regarded as an improvement upon my prior Patent No. 992,208, dated May 16, 1911, and is adapted for attachment to the rotatable spindle of a spinning machine, and includes a roller that forms the operative face of the tool, being mounted in axle alignment with the spindle and projected slightly, to freely engage the end of the work to form a head upon the rivet.

My patent above referred to, like some other inventions for similar purposes, employs a pair of rollers in a holder for working upon the rivet head, both of said rollers being mounted upon the same horizontal bearing, though free to turn in opposite directions. The theory of the action is to work on opposite edge portions of the rivet at the same time. I find with that form of spinning head the rollers, if not already separated, will in time separate, with respect to each other, and in operation consequently form a tit on the center of the top of the rivet head, being formed, and will thus not produce a smooth surfaced head, as is desired.

I have therefore endeavored to overcome this difficulty by using a relatively larger single roller whose diameter is greater than one side portion than the other and wherein the face of the larger diameter is concaved and the smaller diameter is straight, said concaved surface merging with the straight surface at the center diameter of the roller.

With these and other objects in view, the invention resides and consists in the construction and novel combination and arrangement of parts hereinafter more fully described, illustrated in the accompanying drawings, and pointed out in the claim here-to appended, it being understood that various changes in the form, proportion, size, and minor details of construction within the scope of the claim may be resorted to

without departure from the spirit, or sacrificing any of the advantages of the invention.

Similar characters of reference denote like or corresponding parts throughout the several figures of the accompanying drawings forming a part of this specification and upon which

Fig. 1 shows a central vertical section through my improved spinning head taken on line 1—1 of Fig. 2; and

Fig. 2 is a further central vertical section through the spinning head, taken at a right angle to Fig. 1.

Referring in detail to the characters of reference marked upon the drawings, 5 indicates the holder having an upper annular shouldered portion 6 for the engagement of a wrench in the attachment of the head to or removal of the head from a spindle, not shown. The holder is further provided with a threaded recess 7 in its upper end portion for its attachment to the rotary spindle of a spinning machine, not shown. The lower end portion of the holder is tapered inwardly and rounded to form a smooth end portion. A transverse pocket 8 is formed in the lower end portion of the holder, forming parallel smooth faced walls between which a roller 9 is rotatably mounted.

This roller is rotatably supported upon a screw 10 which passes through aligned transverse holes 11 and 12 of the two side members 13 and 14. The hole 11 serves to receive the head end of the screw and the threaded hole 12 to receive the reduced threaded end of the screw, for retaining the same and the roller within the holder. *a* represents the larger portion or operative face of the roller, and *b* the smaller portion or inoperative face so that when a rivet as indicated by dotted lines in Fig. 2, is being operated upon, the operative face of the roller will operate upon the entire end and head of the rivet. The roller may be so shaped and proportioned that substantially one half the face is concave and the remaining half of a lesser diameter, in cross section. It is important that the roller be positioned so that the center of its diameter is in line with the axis of the holder

which brings the larger diameter of the roller to roll upon one side of the head only, the center of the head acting as an axis upon which the roller spins. The larger and curved portion of the roller serves first to break down the annular edge of the rivet and then spread the same out to form a relatively wide rivet head of any desired size and proportion having a smooth rounded upper surface. By 10 using a single roller in this manner the forming of objectionable pits upon the top of the head is eliminated and the forming of a perfect head is assured.

Having thus described my invention, what 15 I claim and desire to secure by Letters Patent is:

In a spinning head for rivet spinning machines, a rotatable holder having a central longitudinal threaded hole for attachment to 20 a vertical spindle, and having a central transverse opening; forming opposite jaws, a bearing mounted in the jaws, a single roller, rotatably mounted within the pocket and upon the bearing and having the center of its 25 diameter in line with the axis of the rotatable holder, said roller being larger through one edge portion than the other and said larger portion having an annular concave surface in cross section, the diameter of the other edge 30 portion of the roller being uniform and having a straight smooth annular surface in cross section.

Signed at Bridgeport in the county of Fairfield and State of Connecticut this 7th day of 35 May, A. D. 1929.

WILLIAM B. MCNAUGHTON.
